AWNNG CENTER SUPPORT

Edward H. Schane, Lakewood, Ohio, assignor to
The Fanner Manufacturing Company, Cleve-
land, Ohio, a corporation of Ohio

Application December 28, 1938, Serial No. 248,089

7 Claims. (Cl. 156—44)

This invention relates to improvements in awning center supports, and more particularly to that type of support where the awning roll is supported upon an endless fabric belt which is rotatable on rollers.

Although the belt type of supports have heretofore been known, there have been many disadvantages present in the prior supports which it is the purpose of the present invention to overcome. For instance, the prior devices had to be adjusted to hold a particular size of awning roll when the fabric was rolled upon it, and when the fabric was unrolled from the awning roll, the support having been adjusted for the larger roll was no longer in contact with the roll and therefore either allowed the awning to sag or furnished no support at all. Furthermore, these previous supports were not so designed that the awning roll was equally supported between the rolls upon which the endless belt was trained, thus the belt did not have as large a peripheral contact as might be desired.

By my present invention I have provided a support whereby the entire support may be rocked to raise or lower the same in relation to the awning roll, making it quick and easy to adjust the same to any sized awning roll. Furthermore, the rolls over which the belt is trained are so arranged and supported that the belt is held under spring tension which increases as the weight of the awning roll increases and where the tension automatically decreases as the weight decreases. The belt always adjusts itself against the roll and at no time is it out of contact therewith.

Still other advantages of the invention and the invention itself will become more apparent from the following description of an embodiment thereof which description is illustrated by the accompanying drawing and forms a part of this specification.

In the drawing:

Fig. 1 is a side view of the device of my invention showing the position taken by the awning roll and fabric;

Fig. 2 is a top plan view thereof with certain parts being broken away and shown in section to better illustrate the interior mechanism;

Fig. 3 is a front elevational view with one of the supporting rolls shown in section; and

Fig. 4 is a side view of a fragmentary portion of one of the arms showing the slot formed therein for the reception of one of the rollers.

Referring now to the drawing throughout which like parts are designated by like reference characters.

A wall bracket 1 is provided and comprises a U-shaped frame, best shown in Fig. 2, having a pair of laterally extending ears 3 through which studs 4 may extend to secure the same to a wall 2. On opposite sides of the frame there are provided forwardly extending members 5 which terminate in ears 6 on opposite sides of the frame spaced parallel to each other.

The frame is adapted to hingeably support a cradle which comprises side members 7 of substantially L-shape, as best shown in Fig. 1. The side members are each apertured at their upper ends 8 and lower ends 9 to receive rods or pintles 10 and 11 journalled in the apertures of the frames and held by cotter keys 12. The pintle 11 extends through the ears 6 pivotally connecting the frames 1 to the wall bracket. The pintles each carries a pulley or roller 13 journalled in bearings, as best shown in Fig. 3.

At the angle of the L the member 7 is formed with slots 14 which extend forwardly in the general direction of the end 9. A roller or pulley 15 carried by the pin 16 is reciprocably journalled in the slot. An endless fabric belt 18 is trained about the peripheries of the rollers 13.

The lower leg of the L-shaped member is provided with an integral cylindrical housing 20 having a bore 21, one end of which is closed by a wall 22, and which bore is in alignment with the slot 14. A screw 23 is threaded in the end wall 22 being provided with a lock nut 24 for holding the same in any desired adjusted position. A helical spring 25 has one end secured about the pintle 16, and the other end extends into the bore 21 where it is seated on a guide member 26. The guide 26 is provided with a head 27 adapted to be engaged by the end of the screw 23.

The wall bracket 1 is also provided at its upper extremity with a forwardly extending lug 30 to which is pivotally connected at 31 a rod or arm 32. A bracket 33 is slidably disposed on the arm 32 and has a yoke 34 which carries a roller 35. The bracket may be secured in any desired position on the arm by a set-screw 36.

The device is used in a manner similar to other awning supports, the bracket being secured to the building at some intermediate point below the awning roll so that the awning roll 40 with the coiled fabric 41 thereon rests in the upper run of the fabric belt. The belt is sufficiently loose about the rollers 13 to provide a continuous contact with the lower surface of the roller and fabric.

The upper roll 35 is adjusted to a position 55 above the awning fabric and guards against the

fabric and roll jumping out of contact with the belt.

The members 7 are also provided with laterally extending ears 42 in which are threaded screws 43 and which are provided with lock nuts. These screws are adapted to extend through the L-frames and abut the downwardly extending portion 44 of the wall bracket. They permit the cradle assembly to be adjusted about the pivotal connection 11 with the wall bracket, thus raising or lowering the belt from under the roll 40—41. In awnings where the roll has a small circumference, the side frames will be adjusted by means of the screw 43 to their outermost position or any intermediate position desired, depending of course on the size of the awning roll.

The awning roll resting on the belt 18 causes the pulley or roll 15 to be pulled forward in the slot 14 against pressure of the spring 25, decreasing the spacing between the rolls over which the belt is trained, and thus allowing a greater length of belt between the upper and forward rollers. As the fabric 41 is rolled upon the roll 40 and the circumference and weight increases, the spring 25 compresses still further allowing the points of connection with the belt and the periphery of the awning fabric to be enlarged, thus lowering the support for the roll as the roll enlarges, at the same time increasing the spring pressure as the weight of the roll increases. The amount of spring pressure is determined by the position of the adjusting screw 23.

It will thus be seen that I have provided a support which may be quickly and easily adjusted to rolls of various diameters during installation, and that after installation the support automatically adjusts itself to the size and weight of the roll and fabric thereon. It will also be seen that at no time is the awning roll without support since as the fabric is removed from the roll and the pressure decreases, the spring automatically takes up the slack in the belt, holding the belt in contact with the roll, furnishing ample support for the roll.

Having thus described my invention I am aware that numerous and extensive departures will be apparent to those skilled in the art, and that although I have described the invention in a particular embodiment thereof, I do not desire to be limited thereby otherwise than is expressed in the appended claims and which claims should be construed with the range of equivalents with which they are entitled in view of the prior art.

I claim:

1. An awning center support embodying a wall bracket, a cradle hingedly connected thereto, comprising, a pair of L-shaped members, a roller mounted in said members at each extremity thereof, another roller loosely journaled in said members intermediate the first named roller, a belt trained over the rollers, an awning roll supported thereby and spaced from said rollers, and means interposed between said members and the intermediate roller to effect a movement of said intermediate roller for tightening the belt as the diameter of the awning roll increases.

2. An awning center support including a cradle hingedly connected to a wall and comprising a pair of spaced side members, rollers journaled in said members at each extremity thereof, another roller journaled in said members intermediate the first named rollers, a belt trained over said rollers, an awning roll resting on the belt intermediate a pair of said rollers and in spaced relation therewith, one of said rollers being

loosely journaled in said members, and spring means connected to said loosely journaled roller and said members to maintain the belt under tension as the diameter of the awning roll varies.

3. An awning center support including a wall bracket, a cradle hingedly supported by the wall bracket and comprising a frame having spaced side members, rollers supported between said side members at the ends thereof, another roller disposed between the side members intermediate the first named rollers and movable towards one of said rollers, an endless belt trained over the rollers, means carried by the side members and engaging the wall bracket for adjustably positioning the cradle relative to the wall bracket, and spring means engaging said movable roller to maintain the belt under spring tension contemporaneous the rolling of the awning fabric onto or from said belt.

4. An awning center support including a wall bracket, a cradle hingedly supported by the wall bracket and comprising a frame having spaced side members, rollers supported between said side members at the extremities thereof, another roller disposed between the side members intermediate the first named rollers, an endless belt trained over the rollers, means carried by the side members and engaging the wall bracket for adjustably positioning the cradle relative to the wall bracket, one of said rollers being movable toward one of the other rollers to decrease the spacing therebetween, spring means engaging said movable roller to maintain the belt under spring tension contemporaneous the rolling of an awning fabric onto or from said belt and an adjustable member for varying the tension on said spring.

5. An awning center support including a wall bracket having a pair of outwardly extending parallel bosses formed to provide axially aligned apertures, a cradle comprising a pair of frames, a pin hingedly connecting said frames to said bosses in spaced parallel relation to each other, a roller supported on said pin, said frame members provided with slots therein below said roller, a roller journaled in the slots for lateral movement thereof, another roller mounted in said frame members and spaced forwardly of the roller disposed in the slots, hollow housings disposed on the sides of said frames in alignment with said slots and having end walls, adjusting screws disposed in said end walls and extending into the interior of said housings, a plug in said housings engaged by said screw and a spring extending into the housing and seated on said plug, the other end of said spring being connected to the roller in said slots and urging it away from the forward roller, an endless belt trained over said rollers and adapted to support an awning roll between the upper and forward rollers, said belt retained under tension by the spring controlled roller during the rolling of the fabric onto or from the belt, said spring controlled roller adapted to be moved against the tension of said spring to allow for an awning roll of greater circumference and a pair of adjusting screws carried by said frames and engaging said wall bracket to adjustably determine the position of the cradle relative to the bracket.

6. An awning center support including a wall bracket having a pair of outwardly extending parallel bosses formed to provide axially aligned apertures, a pair of frames joined together by a roller to form a cradle, said cradle being hingedly supported by the bosses in the bracket, a roller

mounted in the forward end of the frames, said frame members formed with slots therein interposed between said rollers, a roller journalled in the slots for movement towards and away from the roller disposed in the forward ends of the frames for decreasing the space therebetween, hollow housings disposed on the sides of said frames in alignment with said slots and having end walls, an adjusting screw disposed in each of said end walls and extending into the interior of the housing, a spring extending into the housing and adjustably engaged by said screw, the other end of said spring engaging the roller journalled in the slots and urging it towards the end of the slot, an endless belt trained over said rollers, the upper run of which is adapted to support an awning roll, said belt retained under tension by the spring controlled roller during the rolling of the fabric onto or from the belt, said spring controlled roller adapted to be moved against the tension of said spring to allow for an awning roll of greater circumference, and a pair

of adjusting screws carried by said frames and engaging said wall bracket to adjustably determine the position of the cradle relative to the bracket.

- 5 7. An awning center support including a wall bracket, a cradle hingedly supported by said wall bracket and including a pair of L-shaped spaced parallel side members, a roller rotatably supported between the side members at each extremity thereof, another roller loosely journalled in said members intermediate said first named rollers, an endless flexible member trained over said rollers, an awning roll floating on the flexible member remote from said rollers, spring means supported by the members and engaging the said intermediate roller to hold said roller under tension against said flexible member to prevent undue sagging of said flexible member at the point of supporting the awning roll when the weight of the roll increases due to the fabric thereon.
